PROCESS FOR DEWAXING OIL

Ulric B. Bray, Palos Verdes Estates, Calif., assignor to Union Oil Company of California, Los Angeles, Calif., a corporation of California

Application November 27, 1931, Serial No. 577,593

8 Claims. (Cl. 196—18)

This invention relates to a process for the separation from petroleum of those hydrocarbons which are normally solid at ordinary temperatures. According to my process I am able to 5 separate from petroleum or mineral oil such substances as asphalt, paraffin, crystalline or amorphous wax, or other gummy substances which may be present. While my process is particularly adapted to the removal of paraffin, 10 amorphous or crystalline wax, or other gummy substances from lubricating oil, it may be utilized in the treatment of any other petroleum fraction where it is desirable to separate the oil from the foregoing substances. Subject matter disclosed herein but not claimed is claimed in the following copending application and patents: Serial No. 466,189, claiming dewaxing with a liquefied normally gaseous hydrocarbon; Serial No. 597,419, filed March 7, 1932, claiming de- 15 asphalting with distillation; Serial No. 705,910, filed January 9, 1934, a division of Serial No. 466,189, claiming wax separation under controlled pressures, centrifuging, alternate chilling and special features of construction; Serial No. 25 707,641, filed January 22, 1934, claiming separation of asphalt or kindred material in conjunction with heating; Serial Nos. 721,602, filed April 20, 1934, and 749,649, filed October 23, 1934, both divisions of Serial No. 466,189 and 20 claiming treatment with butane; Patent No. 1,944,491 claiming separation of asphalt and wax; Patent No. 1,949,989, claiming asphalt separation; Patent No. 2,006,098, claiming chemical treatment in conjunction with propane treatment; and Patent No. 2,031,204, claiming propane 25 treatment in conjunction with the use of heavier solvent materials.

Many crude oils from which lubricating oil is 30 produced contain paraffin or wax. It is found associated with the lubricating oil fractions of paraffin base crude oil and with the lubricating oil fractions produced from many of the mixed base and asphalt base crude oils. It is not only 35 of doubtful lubricating value but limits the temperature at which lubricants containing it may be used by congealing at the lower temperatures. Therefore, in the production of lubricating oil from petroleum fractions containing wax or paraffin, it is customary, at the present time, to remove a substantial portion of the wax or paraffin 40 present in the oil in order to lower the temperature at which the final product congeals. The temperature at which an oil congeals is commonly 45 referred to as its "pour point" and this value is 50

usually obtained according to method D97—30 of the American Society of Testing Materials.

Several methods well known in the art are employed at present for the production of low "pour point" lubricating oil stock from petroleum 5 fractions which contain substances congealing at high temperatures as set forth above and to which I shall hereinafter refer as wax. One of the oldest methods which has been used is the cold settling process. The wax-containing oil is 10 first diluted with a substantial quantity of light hydrocarbon diluent such as naphtha, gasoline or kerosene. The diluted oil and wax are then run into a tank of large capacity and slowly chilled by the aid of brine circulated in coils located 15 within the tank. The chilling process is carried out for a period of from 20 to 50 hours until a temperature is reached at which there exists a substantial separation of the wax in the form of a slime or gel from the solution of oil. By allowing the cold solution of oil containing precipitated wax to stand for a period of several weeks 20 the precipitated wax settles to the bottom of the chilling tank. While this method has been used extensively for the separation of wax from lubricating oil it is objectionable because of the cost of refrigerating the diluted oil over so long a period, furthermore because of the large tank and refrigeration capacity required for the treatment of the oil and lastly on account of the usual 25 poor separation obtained between the wax and the oil.

Another method for dewaxing petroleum which has been used to a large extent is known as the cold pressing process. Wax distillate produced 30 from those fractions of petroleum distilling over between the approximate temperature limits of 45° F. and 67° F. is chilled slowly to a temperature of about 15° to 30° F. whereupon the wax present in the oil precipitates to form a 35 product having a mushy consistency. The cold mushy mass is then pumped through a filter press under a pressure of 300—350 pounds per square inch. The wax present is collected upon the filter and the oil is recovered as a pressed 40 distillate relatively free from wax. When the oil under treatment contains a relatively large quantity of wax it is sometimes necessary to re-chill and re-filter it in order to obtain an oil having the desired pour point. The length of time 45 required to filter the chilled oil depends upon the crystalline structure of the wax. A distillate which is poorly crystallized, i. e., with crystals in the form of plates, or in which the wax crystals are small requires a much longer period of fil- 50 55

- tration than does a distillate in which the wax crystals are large and of needle structure. This process has found commercial application only in conjunction with oils having the wax present 5 in a crystalline form, as so-called amorphous wax or micro-crystalline wax is extremely difficult to separate by filtration from oil. Consequently oils containing amorphous wax cannot be treated on a commercial scale by this process.
- 10 In the production of the wax distillate the distillation step is usually sufficient to convert the wax from an amorphous to a crystalline state or more probably to destroy crystallization inhibitors, which changes afford quick separation of the 15 wax from the chilled oil in the filter presses. However, in some cases, distillation of the wax is insufficient to produce the proper crystalline structure required for practical filtration, in which case it becomes necessary to expose the 20 wax distillate to a cracking operation.

Another process has been suggested which consists in diluting the oil containing wax with such light petroleum hydrocarbons as gasoline, naphtha or kerosene, adding to the diluted oil a wax- 25 adherent material, chilling the mixture of oil and wax-adherent material with constant agitation until a temperature is reached which is sufficiently low to cause the wax present in the oil to precipitate and collect upon the wax-adherent 30 material and finally separating the substantially wax-free oil by filtration from the wax-adherent material and wax. Again this process is objectionable because of the long period of time required to obtain suitable wax separation from the 35 diluted oil and also because of the large chilling and filtering capacity required to make the process commercially possible.

I have discovered that many of the disadvantages present in the foregoing processes which I have described may be overcome by removing the 40 waxy constituents of petroleum according to the process which I am about to describe.

Paraffin and wax are more soluble at low temperature in the heavy hydrocarbons, i. e., hydrocarbons of high molecular weight, than in the light hydrocarbons, i. e., hydrocarbons of low molecular weight. Thus the solubilities of these materials at low temperatures are greater in kerosene than in gasoline and appreciably greater 45 in gasoline than in a light hydrocarbon such as liquid propane. When oils containing wax are dissolved in such solvents as kerosene or gasoline and chilled to a temperature of 0° F. or lower, the wax present slowly precipitates out of solution. Consequently a long period is usually required 50 to obtain substantial precipitation of the wax from solution. Where lighter solvents are employed as diluents for the waxy oil, the period of refrigeration is materially lessened and the 55 precipitation of the wax from solution is more complete. I have discovered that liquid propane is an ideal diluent for the precipitation of wax from wax bearing oil at low temperatures. Owing to its poor solvent power for wax at low temperatures, it is very desirable as a diluent in the precipitation of wax from waxy oils at low temperatures. It is especially desirable for this purpose because once the propane solution of waxy oil has reached the desired dewaxing temperature 60 the wax present in the solution immediately precipitates out. Long periods of refrigeration which add greatly to the cost of dewaxing the oil are thus avoided.

I have discovered that wax which has been 75 precipitated from a propane solution of waxy

oil differs in physical structure from wax which has been precipitated from waxy oil dissolved in heavier solvents such as gasoline or naphtha. Waxes which have been precipitated from gasoline or naphtha by chilling a residual waxy oil 5 dissolved in these solvents are usually highly amorphous in structure. They are in the nature of gels or slimes and as such offer many difficulties in their removal from the chilled solution of oil and solvent. As has already been pointed 10 out they are unusually hard to separate by ordinary filtration methods as the slimy wax forms an impervious layer upon the filter plate of the filter press which obstructs free movement of the dewaxed oil through the filter plate, and filtration 15 is usually possible only if excessive amounts of filter aid are employed. Furthermore, the wax flocks or aggregations which are formed during the chilling operation will not settle out by cold settling methods sufficiently to produce a finished 20 oil of the desired pour point because of the slight difference in the specific gravity between the solution of oil in the solvent and the wax. However, when the wax is precipitated by chilling waxy oil dissolved in propane it possesses a highly 25 granular structure. While it may not be macro-crystalline in character yet it is unlike the wax produced by chilling a waxy oil dissolved in naphtha or gasoline in that it appears to be composed of discrete particles. 30

Due to the granular structure which the wax possesses when precipitated from a chilled propane solution of waxy oil it may be separated commercially from the propane solution of oil by filtration with none of the attending difficulties 35 present when filtering waxy slimes from chilled gasoline, naphtha, or relatively heavy hydrocarbon solutions of oil. The granular structure of the wax precipitated from the chilled propane solution of waxy oil does not form the impervious 40 film over the filter plate which is characteristic of waxy slimes or gels precipitated from chilled solutions of waxy oil dissolved in such solvents as gasoline or naphtha. Instead such granular waxes form a porous layer upon the filter plate 45 through which the wax-free oil dissolved in solvent may freely flow.

In some instances I find it advantageous to precoat the plates or the filter with such filter aids as diatomaceous earth, fuller's earth, clay, 50 wood flour or sawdust prior to filtration. By depositing a thin layer of any of the foregoing materials upon the filter plate prior to passing the chilled mixture of propane and oil containing precipitated wax through the filter I am able to 55 obtain a more thorough separation of the granular wax from the oil dissolved in propane. In carrying out this type of operation I first mix a small quantity of the precoating materials such as diatomaceous earth, fuller's earth, clay, wood- 60 flour or sawdust with liquid propane and pass this mixture through the filter. The precoating substance suspended in the liquid propane deposits itself in a thin layer over the filter plate and the propane is withdrawn from the filter 65 press as a clear filtrate. The chilled oil dissolved in liquid propane carrying precipitated wax in suspension is now forced through the filter press and the precoating materials present on the filter plates aid in separating the wax from the propane solution of oil. While I may employ any of the foregoing materials as precoating substances for the filter press, I have found wood flour to be especially well adapted for this purpose. 70

Furthermore, due to the difference in specific 75

gravity between the precipitated granular wax and the propane solution of oil, I am able to obtain satisfactory separation of the precipitated wax and the solvent solution of oil by ordinary settling methods as contrasted with relatively unsatisfactory results in case heavier solvents, such as naphtha or gasoline, are employed as diluents for the waxy oil. The long settling period necessary to obtain separation of the precipitated wax from the gasoline or naphtha solution of oil is obviated by the substitution of liquid propane for the gasoline or naphtha as diluent. Due to the granular form in which the wax precipitates from the chilled propane solution of waxy oil and furthermore due to the difference in specific gravity between the precipitated wax and the propane solution of oil, rapid separation by gravity may be obtained of the precipitated wax from the propane solution of oil. This makes possible the elimination of the large settling capacity which is necessary in the cold settling process for the separation of wax from oil. The cold settling process is essentially a batch process; that is to say large volumes of waxy oil dissolved in such solvents as gasoline or naphtha are chilled to a temperature sufficiently low to precipitate a portion of the wax present, after which the mass is allowed to remain in a quiescent state for several weeks in order to allow the wax to settle out. Owing to the rapid rate at which the precipitated granular wax separates out of the chilled oil dissolved in liquid propane, I am able to operate my dewaxing process continuously. By continuously feeding a chilled mixture of wax and oil dissolved in liquid propane to an ordinary vapor tight settling chamber it is possible to separate the precipitated wax from the propane solution of oil.

Another advantage of using a liquid hydrocarbon as a diluent for the wax containing oil is that by allowing a portion of the solvent to vaporize under reduced pressure all the necessary refrigeration is obtained to chill the oil to the desired dewaxing temperature. The waxy oil is first dissolved under pressure in a light liquid hydrocarbon. A portion of the light liquid hydrocarbon is vaporized or allowed to boil off at reduced pressure and thereby lowers the temperature of the waxy oil dissolved in the remaining solvent to a point sufficiently low to precipitate the wax. Thus the light liquid hydrocarbon functions as a diluent for the wax-bearing oil and also as an internal refrigerant to chill the solution of oil and wax to the proper dewaxing temperature. When I use the term "light liquid hydrocarbon" I mean those hydrocarbons which are normally in the vapor state at atmospheric pressure and temperature. Such hydrocarbons include propane, isobutane, butane, ethane, methane and mixtures thereof. These may be obtained by the rectification of casinghead gasoline by the so called "stabilizing method." They are the overhead thus obtained. They are liquefied by compression and cooling in the conventional manner and drawn off into pressure chambers where they are maintained in a liquid state until they are used. A typical analysis of such a solvent is 6.72% ethane, 72.20% propane, 19.91% isobutane and 1.17% normal butane. Hereafter for convenience such a fraction will be referred to as "propane." However, it is to be understood that I do not propose to limit myself to a solvent having the foregoing composition as the percentage of the individual hydrocarbon members of the solvent may vary more or less.

It is therefore an object of my invention to precipitate granular wax from wax-bearing oil and separate said wax from said oil.

It is another object of my invention to precipitate granular wax from wax-containing oil by the use of a solvent and to separate said wax from the oil and solvent.

It is another object of my invention to precipitate wax in a finely granulated form from wax-bearing oil by the use of liquid propane and subsequently to separate the wax, oil and propane from each other.

It is another object of my invention to precipitate wax from oil containing wax by the use of liquid propane, separate said wax from said oil and propane by the aid of a filter plate precoated with a filter aid and subsequently separate the substantially wax-free oil from the propane.

It is still another object of my invention to dissolve waxy oil in liquid propane under pressure, cool the waxy oil dissolved in liquid propane to a temperature sufficiently low to precipitate granular wax by allowing a portion of the propane to vaporize under reduced pressure, separate the wax from the oil dissolved in liquid propane and subsequently separate the propane from the substantially wax-free oil.

It is still another object of my invention to dissolve oil containing wax under pressure in liquid propane, and chill the propane solution of oil to a temperature sufficiently low to precipitate wax by vaporizing a portion of the propane under reduced pressure, impose sufficient pressure upon the cooled solution of oil and precipitated wax to prevent further vaporization of propane, separate the wax from the oil dissolved in liquid propane and subsequently separate the propane from the substantially wax-free oil.

Fig. 1 is a schematic arrangement of one form of apparatus for carrying out my invention.

Fig. 2 is a schematic arrangement of another form of the apparatus in which my process may be carried out.

Referring more particularly to Fig. 1, waxy oil above its congealing point in tank 1 is withdrawn through line 2, valve 3, line 4 and sent by means of pump 5 through line 6 into agitator 7 where the waxy oil is dissolved in liquid propane coming from tank 10 by means of line 11, pump 12, line 13, valve 14 and line 15. The waxy oil dissolved in liquid propane passes from agitator 7 into separator 55 where any undissolved asphalt present in the oil is permitted to settle out and is withdrawn through valve 56 and line 57. The waxy oil dissolved in liquid propane passes from separator 55 through line 8 into chiller 9. The waxy oil dissolved in liquid propane is cooled to a temperature sufficiently low to precipitate a substantial portion of the wax present by allowing a portion of the liquid propane present to vaporize under reduced pressure through line 16 and valve 17, from whence it passes to compressor 18, which forces it through line 19 to condenser 20 where it is liquefied and passes by means of line 21 to propane storage tank 10. During the chilling operation in chiller 9, sufficient propane is vaporized to reduce the pressure within the chiller to approximately atmospheric pressure.

The chilled solution of oil dissolved in liquid propane containing the precipitated granular wax is withdrawn from chiller 9 through valve 39, line 48 and sent by means of pump 40 through line 41, valve 42, and line 29 to filtering chamber 30. The pressure upon the mixture of oil dissolved in propane and precipitated wax in filtering

chamber 30 is increased to a point sufficiently high to cause all boiling or ebullition within this chamber to cease by maintaining sufficient pressure within chamber 30 by operation of pump 40. After the chilled oil in filtering chamber 30 has remained in a quiescent state for a short period under sufficient pressure to inhibit boiling or ebullition, valve 31 is opened and the wax-free oil passes through filter plate 49 into line 32 from whence it passes to pump 33 which forces it through valve 34 and line 47 into heater 34, vaporizes all of the propane present by means of steam which is introduced through closed steam coil 43. The vaporized propane passes from heater 34 through line 35 to compressor 36 which forces it through line 37, valve 38, line 19 to condenser 28 where it is condensed and passes through line 21 to propane storage tank 10.

The dewaxed and propane-free oil in heater 34 is removed through valve 54 and sent by line 45 to tank 46.

The wax cake in filtering chamber 30 is removed, after which another charge of chilled oil, containing precipitated wax from chiller 9, is introduced and the dewaxing operation is repeated.

As a modification of the foregoing process I sometimes find it desirable to precoat filter plate 49 of filtering chamber 30 prior to introducing the chilled propane solution of oil and precipitated wax. Liquid propane from tank 10 passes by means of line 11 to pump 12 which forces it through valve 22, line 23, to agitator 25 where it is mixed with such precoating materials as kieselguhr, diatomaceous earth, fuller's earth, clay or wood flour introduced through line 24. The precoating material suspended in liquid propane passes through line 26, valve 27, line 28 and line 29 into filtering chamber 30 where the precoating material is deposited in a layer upon plate 49. The propane is withdrawn through valve 31 and line 32 to pump 33 which forces it through line 50, valve 51 and line 52 to propane storage tank 10.

After the filter plate in filtering chamber 30 has been covered with a layer of precoating material, the chilled oil dissolved in propane carrying precipitated wax is withdrawn from chiller 9 through valve 39 and line 48 into pump 40, which forces it through line 41, valve 42 and line 29 into chamber 30 from whence it is forced through the precoated filter plate 49 which retains the precipitated wax and allows the propane solution of oil to pass freely through valve 31 and line 32 to pump 33 which forces it through valve 53 and line 47 to heater 34 where the propane is separated from the dewaxed oil.

Referring more particularly to Fig. 2, waxy oil from tank 100 at a temperature above its congealing point passes by means of line 102, valve 103 and line 104 to pump 105, which forces it through line 106 into agitator 107 where it is dissolved in liquid propane coming from tank 110 through valve 111, line 112, pump 113, line 114, valve 149 and line 106. The waxy oil dissolved in liquid propane passes from agitator 107 into separator 159 where any undissolved asphalt present in the oil is permitted to settle out and is removed through valve 160 and line 161.

The propane solution of waxy oil passes from separator 159 into line 108 from whence it passes into chilling tank 109. By opening valve 116 and allowing a portion of the propane present in chilling tank 109 to vaporize, the temperature of the waxy oil dissolved in the liquid propane is lowered sufficiently to cause precipitation of the

wax. The vaporized propane is removable through line 117 to compressor 118 which forces it through line 119 to condenser 120 where it is liquefied and passes by means of line 121 to propane storage tank 110.

The chilled oil dissolved in propane carrying the precipitated wax is removed from chiller 109 through line 122, valve 123 and line 124 to pump 125, which forces it through line 126 into the vapor tight wax separator 127. In order to prevent boiling or ebullition in the wax separator during the wax settling operation, pressure is imposed upon the solution of oil. This is accomplished by maintaining pressure within the separator by pump 125. As the chilled mass in the wax separator remains in a non-ebullient state the wax settles out and is collected by vanes 130 which remove it through valve 132 and line 133. The wax-free oil dissolved in propane is withdrawn from the separator 127 into line 135, valve 136, line 138 to pump 137 which forces it through line 139 into heater 139 where the propane present is vaporized by aid of steam introduced through closed steam coil 140. The vaporized propane passes out of the heater through line 141 to compressor 142 which forces it through line 143, valve 144, and line 119 to condenser 120 where it is liquefied and passes by means of line 121 to propane storage tank 110. The dewaxed propane-free oil passes from heater 139 by means of line 145, valve 146 and line 147 into tank 148.

As an example of the preferred method of carrying out my process Santa Fe Springs crude oil topped to a viscosity of 100 seconds, (Saybolt Universal at 100° F., on stream) is withdrawn from tank 100 and mixed in agitator 107 with liquid propane withdrawn from tank 110 in the proportion of one volume of the topped crude oil to six volumes of liquid propane. The agitated mass is passed into settling chamber 159 where the asphalt precipitates out and is withdrawn through valve 160 and line 161. The propane solution of waxy oil passes from the settling chamber 159 into chilling tank 109. Valve 116 is opened and propane is vaporized until the proportion of propane to oil is about four to one. By this time the temperature of the chilling tank will have fallen to about -35° F. if a reasonably pure liquid propane has been used. The vaporized propane in line 117 is forced by compressor 118 through line 119 into condenser 120 where it is liquefied and passes into propane storage 110. The chilled propane solution of oil and precipitated wax is withdrawn from chilling tank 109 through line 122 and forced by pump 125 into the wax separator 127. By maintaining sufficient pressure upon the liquid in separator 127 all ebullition ceases, the wax present settles out and is removed by vanes 130 into line 133. The oil and solvent pass out of the wax separator through line 135 and are forced by means of pump 137 into heater 139 where the propane is separated from the oil with the aid of steam introduced through closed coil 140. The asphalt and wax-free oil passes from heater 139 through line 145, valve 146 and line 147 into storage tank 148. The vaporized propane from heater 139 passes by means of line 141 to compressor 142 which forces it through lines 143 and 119 to condenser 120 where it is liquefied and passes by means of line 121 into propane storage tank 110.

It is to be understood that the foregoing example is merely illustrative of one method of carrying out my invention and must not be construed as limiting upon the invention which I

claim as many modifications will appear to those skilled in the art.

What I claim is:

1. A process for separating wax from a wax-oil mixture which comprises forming a chilled mixture of separated wax and oil diluted with a liquefied normally gaseous hydrocarbon diluent having an average molecular weight greater than that of ethane and at least as low as that of butane and filtering the chilled mixture to remove said separated wax from the diluted oil.

2. A process according to claim 1 in which the liquefied normally gaseous hydrocarbon diluent consists chiefly of liquid propane.

3. A process of removing wax from a wax-oil mixture which comprises diluting an oil-wax mixture with a liquefied hydrocarbon diluent which has a vapor pressure higher than that of butane and lower than that of ethane, chilling the mixture to precipitate wax and filtering the chilled mixture to remove the precipitated wax from the chilled mixture.

4. A process of separating wax from a wax-bearing oil which comprises mixing said oil with a liquefied hydrocarbon diluent composed chiefly of propane and having a vapor pressure substantially equal to that of propane, chilling the mixture to precipitate wax and filtering the chilled mixture to remove said precipitated wax from the chilled mixture.

5. A process of removing wax from a wax-oil mixture which comprises diluting an oil-wax mixture with a liquefied hydrocarbon diluent which has a vapor pressure higher than that of butane and lower than that of ethane, evaporating a portion of said hydrocarbon diluent in direct contact with the oil-wax mixture whereby the oil-wax mixture is chilled to precipitate the wax

and filtering the chilled mixture to remove the precipitated wax from the chilled mixture.

6. A process for separating wax from a wax-oil mixture which comprises forming a chilled mixture of separated wax and oil diluted with a liquefied normally gaseous hydrocarbon diluent having an average molecular weight greater than that of ethane and at least as low as that of butane and filtering the chilled mixture in the presence of a filter aid to remove said separated wax from the diluted oil.

7. A process for the separation of wax from a wax-oil mixture which comprises dissolving said oil under pressure in a liquefied normally gaseous hydrocarbon diluent consisting predominantly of propane, releasing the pressure and vaporizing a portion of said diluent to lower the temperature of the wax-oil mixture sufficiently to precipitate wax, maintaining diluent in sufficient quantities to permit ready filtration, filtering the chilled mass through filter aid to remove the wax and subsequently separating filtrate into diluent and dewaxed oil.

8. A process for the separation of wax from a wax-oil mixture which comprises diluting said wax-oil mixture with a liquefied normally gaseous hydrocarbon diluent consisting preponderantly of propane under temperature and pressure conditions sufficient to prevent substantial evaporation of said liquid diluent, agitating the mixture and effecting solution of the wax-oil mixture in the diluent, chilling the solution to a temperature sufficiently low to precipitate the wax, maintaining the diluent in amount sufficient to thin the oil to permit ready separation of the wax and filtering the chilled mixture to remove the wax from the diluted oil.

ULRIC B. BRAY.
